UNITED STATES PATENT OFFICE.

LARS W. BODINSON, OF AURORA, ILLINOIS, ASSIGNOR TO THE AMERICAN WELL WORKS, OF AURORA, ILLINOIS, A CORPORATION OF ILLINOIS.

CENTRIFUGAL PUMP.

1,155,401.

Specification of Letters Patent.

Patented Oct. 5, 1915.

Application filed April 29, 1911. Serial No. 624,018.

To all whom it may concern:

Be it known that I, LARS W. BODINSON, a citizen of the United States, residing at Aurora, in the county of Kane and State of Illinois, have invented certain new and useful Improvements in Centrifugal Pumps, of which the following is a specification, reference being had to the accompanying drawings.

16 My invention relates to deep well pumps, and has for its object to provide certain improvements in pumps of the centrifugal type, as hereinafter set forth. I accomplish this object as illustrated in the drawings and 15 as hereinafter described.

What I regard as new is set forth in the claims.

In the accompanying drawings, Figure 1 is a sectional view illustrating the upper 20 portion of my improved pumping apparatus in place in a well, the motor being in elevation: Fig. 2 is a sectional view of the lower portion of the pumping apparatus, being a continuation of the illustration in Fig. 25 1: Fig. 3 is an enlarged sectional detail: Fig. 4 is an enlarged detail of the lower end portion of the pumping apparatus, some parts being in elevation: and Fig. 5 is a similar view of the intermediate portion of 30 the pumping apparatus.

My improved pump is of the type in which there is a pump-shaft extending down into the well through a pump tube or casing and is provided with one or more pumping 35 units which, by the rotation of the shaft, act to elevate the water. In pumps of this character it is necessary to protect the pump-shaft from accumulation of sand or other solid material around the shaft with the 40 consequent cutting or wearing away thereof, and it is also necessary to provide suitable bearings by which the pump-shaft is held properly in alignment and to provide adequate means for lubricating such bearings. 45 My present invention has to do with improved means of securing these results as well as to provide other improvements, which will be hereinafter pointed out.

Referring to the drawings, 6 indicates the well, which is usually provided with a well-tube or casing 7, as shown in Figs. 1 and 2.

8 indicates a tube or pipe which extends down into the well and serves as a discharge pipe for the water. The tube 8 is made in sections united by couplings 9, with which

they have screw-threaded connections, as shown. As best shown in Fig. 2, said couplings comprise two members suitably secured together, as by bolts, and having respectively upwardly and downwardly extending annular flanges into which the sections of the tube 8 are screwed. 60

10 indicates a discharge section or elbow, which is connected with the upper end of the tube 8, preferably by a coupling 11, as 65 shown in Fig. 1. The section 10 is preferably formed as a part of a pedestal 12 which forms a main support for the pump-rod or shaft hereinafter described. The pedestal 12 rests upon a bed-plate 13 which rests 70 upon a suitable foundation 14.

15 indicates a pump rod or shaft, which is also made in sections connected by couplings 16, and at its upper end projects through a bearing 17 carried by the pedestal 75 12, and is connected by a flexible coupling 18 of any suitable type with a motor 19 by which it is rotated. The weight of the shaft 15 is sustained by an anti-friction bearing composed of upper and lower plates 20—21, 80 respectively, the lower plate being mounted in a suitable support 22, the upper plate resting on the lower plate and supporting a collar 23 which is screw-threaded upon the pump-shaft 15 so as to be adjustable longitudinally thereof. By adjusting the collar 85 23 the shaft 15 may be raised or lowered to secure vertical adjustment thereof.

24 indicates a lock-nut screwed upon the shaft 15 above the collar 23. 90

25 indicates a pipe for conducting oil to the plate 22 for lubricating its anti-friction bearing, said pipe being provided with a glass tube 26 by which the level of the oil may be observed. 95

27 indicates a tube which surrounds the pump-shaft 15 and forms a casing therefor to protect it from water, sand, etc. Said casing is also made in sections which are united by bearing coupling blocks 28, having threaded ends to receive the ends of the casing. The blocks 28 are slidably fitted in sleeves 9—11 with which the couplings 9 and 11 are provided. Thus the latter couplings serve to center the casing in the discharge pipe 8. 100

29 indicates a stuffing-box at the upper end of the casing 27 for preventing the escape of water around said casing.

30—31 indicate upper and lower pumping 105

units composed of chambers 32—33, respectively, in which are mounted rotating runners 34—35 carried by the pump-shaft 15. The units 30—31 are arranged in the form of a pile, one above another, any desired number being employed,— (in the drawings I have shown only two),—the water passing from the lower unit to the one next above it under the action of the rotating runners.

36 indicates a discharge chamber above the upper unit 30 and communicating therewith and with the lower end of the discharge pipe 8, as shown in Fig. 2. The casting which forms the discharge chamber 36 is provided with a central sleeve 37 which forms a bearing for the shaft 15 and communicates at its lower end with transverse passages 38 which extend from the shaft 15 to the well, the purpose of these passages being to prevent water from gaining admission into the casing 27 by allowing it to pass out through said passages 38 into the well. The lower end of the casing 27 is tightly connected with the sleeve 37 in any convenient way, preferably by screw-threads, as best shown at 39 in Fig. 5. As also shown in said figure, the sleeve 37 is provided with a bushing 40, preferably of brass, which takes the wear and may be easily replaced.

41 indicates a gland fitted into the lower end of the sleeve 37 and held in place by bolts 42, as best shown in Fig. 5.

43 indicates a sleeve, which is fitted upon the shaft 15 below the bushing 40, which sleeve also forms a bushing to take the wear. The sleeve 43 is perforated, as shown in dotted lines at 44 in Fig. 5, so that water and oil which enter the space between the casing and the shaft 15 may pass out into the transverse passages 38.

45 indicates packing in the form of flanged disks which are provided upon the sleeve 43 and are held in place by the gland 41 and a spring 45^a, as shown in Fig. 5.

46 indicates a bearing for the lower end of the pump-shaft 15, said bearing being mounted in a suction-chamber 47 which communicates with the lower pumping unit 31. The construction of the lower bearing 46 is best shown in Fig. 4, from which it will be seen that the lower end of the pump-shaft is provided with a sleeve 47^a which is held in place by nuts 48—49 screwed upon the lower end of the pump-shaft, said sleeve fitting in the bearing 46, which is provided with a bushing 50, preferably in the form of a brass tube. The bearing 46 is held in place by webs 51 cast integral with the casing of the suction-chamber 47.

52 indicates a gland, which is fitted over the upper end of the bearing 46 and is held in place by bolts 53. Packing 54 similar to the packing 45 is provided around the sleeve 47 and is compressed by the gland 52 against a spring 55, as shown in Fig. 4.

56 indicates a cap, which is screwed upon the lower end of the bearing 46 and incloses the lower end of the pump-shaft 15.

56^a indicates a cap which is fitted upon the sleeve 47^a and is secured thereto by a set-screw 56^b, as best shown in Fig. 4. The cap 56^a has a depending flange 56^c which fits over an upwardly-projecting flange 52^a on the gland 52, thereby affording protection against the admission of sand to the bearing. The flange 56^c is provided with outwardly-projecting wings 56^d. As the sleeve 47^a and cap 56^a rotate with the shaft 15, the wings 56^d serve to throw sand and other gritty matter outwardly from the shaft, and thereby further protect the lower bearing from injury by the admission of such gritty substances to it.

It will be noted from the foregoing description that the lower shaft bearing is entirely inclosed and protected, but the shaft is still capable of being vertically adjusted, as hereinbefore described. It will be noted, further, that the several runner chambers are interposed between the lowermost shaft bearing 46 and the shaft bearing 37, both of which are protected against the admission of sand. The upper bearing is further protected by the transverse passages 38 which, as hereinbefore described, permit water to pass out into the well without going up into the bearing 37, so that any sand carried by the water is discharged into the well and does not reach said bearing. By this construction the bearings are not cut out or injured to any appreciable extent as compared with other pumps of a similar type in which the same protection is not afforded.

57 indicates a supply-pipe, which communicates with the suction chamber 47 and extends down into the well.

In order to lubricate the several bearings, I provide an oil reservoir 58 having a pipe 59 which extends down into the well and communicates with the several bearings. A branch pipe 60 extends from the pipe 59 to a chamber 61 which contains the stuffing-box 29, for supplying oil to the casing 27 around the pump-rod, and a branch pipe 62 extends from the pipe 59 to the bearing 37, as shown in Fig. 2. The lower end of the pipe 59 extends into the bearing 46. It will be noted that by this construction the several bearings are lubricated, as oil being admitted to the casing 27 at its upper end, passes down therein to the several intermediate bearings throughout the length of the pump-shaft. The oil is also admitted directly to the bearings 37 and 46. By the use of the packing in the bearings 37 and 46 the oil is held in said bearings so that it does not readily escape.

In Fig. 3 I have presented an enlarged view illustrating the construction of the several couplings 9, the manner in which the oil

is allowed to pass through them, and means by which oil that may accumulate above the sleeve 28 may be withdrawn when the sections of the shaft casing are being disconnected, so as to prevent it from flying out over the workmen. As therein shown, the sleeve 28 is provided with a longitudinal passage 63 through which the oil may flow through said sleeve. At the upper end of the passage 63 a perforated plug 64 is provided which projects slightly above the upper end of the sleeve and consequently serves to retain a small quantity of oil in the casing above the sleeve. As shown in Fig. 3, the end portions of the sleeve 28 are screw-threaded so that the casings 27 screw thereupon—the upper section of the casing being illustrated in said figure as almost wholly unscrewed from the sleeve. When so unscrewed, an opening in the side of the screw-threaded portion of the sleeve is exposed which is adapted to receive a pipe 65 which is screwed thereto, as shown in said figure. Consequently any oil that may have accumulated in the casing 27 above the sleeve 28 owing to clogging of the passage 63, may be withdrawn through pipe 65. When the upper section of the casing 27 is screwed down upon the sleeve 28, such opening is closed thereby.

In order to prevent the sleeve 28 from turning when the casing section 27 is being unscrewed, I provide a rod 66 which fits in a suitable socket provided in the side of the sleeve, as shown in Fig. 3, and may be locked to the coupling 9 by a pin 67 which drops through an eye in the rod 66 into engagement with the coupling, which, as shown in Figs. 2 and 3, is in the form of a spider. Thus the sleeve 28 may be non-rotatably secured to the coupling 9 so that it does not turn when the section 27 is unscrewed.

The couplings 9 are made of two separable members suitably secured together by bolts or other equivalent devices so that they may readily be taken apart when desired.

That which I claim as my invention, and desire to secure by Letters Patent, is,—

50 1. In a centrifugal pump, the combination of a sectional water conducting pipe, a coupling connecting the sections of said pipe together, a pump-shaft extending down through said pipe, rotary water elevating devices carried by said pump-shaft, a sectional casing inclosing said shaft, and bearings for said shaft connecting the sections of the casing together, said bearings being centered by said coupling and having a sliding engagement therewith.

2. In a centrifugal pump, the combination of a sectional water conducting pipe, a coupling connecting the sections of said pipe together, a sleeve carried by said coupling, a pump-shaft extending down through said

pipe, rotary water elevating devices carried by said pump-shaft, a sectional casing inclosing said shaft, and bearings for said shaft fitted in said sleeve.

3. In a centrifugal pump, the combination of a sectional water conducting pipe, a coupling connecting the sections of said pipe together, a sleeve carried by said coupling, a pump-shaft extending down through said pipe, rotary water elevating devices carried by said pump-shaft, a sectional casing inclosing said shaft, and bearings for said shaft slidably fitted in said sleeve.

4. In a centrifugal pump, the combination of a sectional water conducting pipe, a coupling connecting the sections of said pipe together, a sleeve carried by said coupling, a pump-shaft extending down through said pipe, rotary water elevating devices carried by said pump-shaft, a sectional casing inclosing said shaft, and a bearing block connecting the sections of the casing together, said bearing block forming a bearing for said shaft and being slidably fitted in said sleeve.

5. In a centrifugal pump, the combination of a sectional water conducting pipe, couplings connecting the sections of said pipe together, a pump-shaft extending down through said pipe, rotary water elevating devices carried by said pump-shaft, a sectional casing inclosing said shaft, the sections of said casing being centered by said couplings, a bearing for said shaft adjacent to the lower end of said casing, one or more passages below said bearing and extending from the shaft to the interior of the well, packing around said shaft between said bearing and said passages, and a gland and a spring for compressing said packing.

6. In a centrifugal pump, the combination of a pump-shaft, one or more runners carried by said shaft, a discharge chamber above the upper runner, one or more passages extending across said discharge chamber from the well to the pump-shaft, bearings for said shaft above and below said passages, and a casing inclosing the pump-shaft above the upper bearing and having no direct communication with the well.

7. In a centrifugal pump, the combination of a pump-shaft, one or more runners carried thereby, chambers in which said runners operate, bearings for said shaft above and below said runners, packing around said shaft below the upper bearing and above the lower bearing, and means for lubricating said bearings.

8. In a centrifugal pump, the combination of a pump-shaft, one or more pumping units carried intermediately by said shaft near the lower end thereof, a casing inclosing said shaft above said pumping units, an anti-friction bearing near the upper end of said shaft for supporting the same, a cylin-

drical bearing in which the lower end portion of said shaft fits and is movable longitudinally, said bearing being closed at its upper and lower ends, and means for vertically adjusting said shaft.

9. In a centrifugal pump, the combination of a pump-shaft, one or more pumping units, near the lower end of said shaft, a bearing for the lower end of said shaft, comprising a sleeve and packing surrounding said sleeve, a gland for compressing said packing, and a cap inclosing the lower end of the shaft.

10. In a centrifugal pump, the combination of a pump-shaft, a sectional casing inclosing said shaft, a coupling comprising a sleeve having its ends screw-threaded to receive the ends of the casing, said sleeve having an oil-passage therethrough, and an external opening at one side of the screw-threaded portion thereof communicating with said oil-passage.

11. In a centrifugal pump, the combination of a pump-shaft, a sectional casing inclosing said shaft, a coupling comprising a sleeve having its ends screw-threaded to receive the ends of the casing, said sleeve having an oil-passage therethrough, an external opening at one side of the screw-threaded portion thereof communicating with said oil-passage, and a perforated plug in the upper end of said passage.

12. In a centrifugal pump, the combination of a pump-shaft, a sectional casing inclosing said shaft, a coupling comprising a sleeve having its ends screw-threaded to receive the ends of the casing, said sleeve having a socket at one side between the threaded portions thereof, a sectional water discharge pipe, and a coupling uniting the sections of said discharge pipe, said sleeve being fitted in said coupling.

13. In a centrifugal pump, the combination of a pump-shaft, pumping units near the lower end of said shaft, a discharge chamber above said pumping units and communicating therewith, a discharge pipe extending upward from said discharge chamber, bearings for said pump-shaft above and below said pumping units, an oil pipe extending down from the surface and connected with said upper and lower bearings, a casing inclosing said pump-shaft, said casing being connected with said upper bearing and having no direct communication with the well, and means for supplying oil to said casing.

14. In a centrifugal pump, the combination of a pump-shaft, one or more runners carried by said shaft, a discharge chamber above the upper runner, a bearing for said shaft above the upper runner, a casing inclosing said pump-shaft and extending upwardly from said bearing, said casing having no direct communication with the well,

one or more passages extending across said discharge chamber from the well to the pump-shaft, and packing around said shaft between said bearing and said passages.

15. The combination with a sectional well-tube, of a coupling uniting the sections of the tube together, said coupling comprising members secured together and having oppositely extending screw-threaded annular flanges adapted to receive the adjacent ends of the well-tube, said coupling members having internal registering sleeves.

16. In a vertical pump of the type described, the combination of a pump-shaft, one or more runners carried by said shaft, a bearing for said shaft below the lowermost runner, a packing gland for said bearing, an imperforate cap supported by the shaft and fitting over the upper end of said packing gland for protecting the same from sand, and means for vertically adjusting the shaft.

17. In a vertical pump of the type described, the combination of a rotary pump-shaft, one or more runners carried thereby, a bearing for the lower end of said shaft, said bearing being closed at its lower end and being disposed in the water-supply passage of the pump, a packing gland for said bearing, and an imperforate cap carried by the shaft and fitted over the upper end of said bearing packing gland.

18. In a vertical pump of the type described, the combination of a rotary pump-shaft, one or more runners carried by said shaft, a bearing for the lower end of said shaft, a packing for said bearing, a gland for securing said packing in place, and an imperforate cap carried by the shaft above said gland for protecting the upper end of the gland against the admission of sand.

19. In a vertical pump of the type described, the combination of a rotary pump-shaft, one or more runners carried by said shaft, a bearing for the lower end of said shaft, a packing for said bearing, a gland for securing said packing in place, and imperforate means carried by the shaft above the gland and rotating with said shaft for throwing gritty substances out from the shaft.

20. In a vertical pump of the type described, the combination of a rotary pump-shaft, one or more runners carried by said shaft, a bearing for the lower end of said shaft, a packing for said bearing, a gland for securing said packing in place, and an imperforate cap carried by the shaft above said gland for protecting the upper end of the gland against the admission of sand, said cap having outwardly-projecting wings.

21. In a vertical pump of the type described, the combination of a series of superposed runner-chambers, a pump-shaft, runners carried by said shaft and operating in said chambers, and bearings for said shaft.

above and below said series of superposed chambers, said bearings being closed at their upper and lower ends against the admission of sand.

- 5 22. In a vertical pump of the type described, the combination of a series of superposed runner-chambers, a pump-shaft, runners carried by said shaft and operating in said chambers, bearings for said shaft above and below said series of superposed chambers, said bearings being closed at their upper and lower ends against the admission of sand, and a passage extending from below the upper bearing to the well.
- 10 23. In a vertical pump of the type described, the combination of one or more run-

ner-chambers, a pump-shaft having one or more runners operating in said chamber or chambers, a shaft-bearing above and adjacent to the uppermost runner, a casing in- 20 closing the shaft and extending upward from the latter bearing, and a passage be- between the uppermost runner and said bearing, said passage communicating with the well for conducting water and gritty sub- 25 stances carried by it out into the well to protect said bearing.

55.

It is hereby certified that in Letters Patent No. 1,155,401, granted October 5, 1915, upon the application of Lars W. Bodinson, of Aurora, Illinois, for an improvement in "Centrifugal Pumps," an error appears in the printed specification requiring correction as follows: Page 4, line 96, claim 17, strike out the word "bearing"; and that the said Letters Patent should be read with this correction therein that the same may conform to the record of the case in the Patent Office.

Signed and sealed this 16th day of November, A. D., 1915.

{SEAL.}

J. T. NEWTON,

Acting Commissioner of Patents.
